UNITED STATES PATENT OFFICE.

EDWARD CLYDE HOWLAND, OF NEW MILFORD, CONNECTICUT.

PUZZLE.

No. 796,426.

Specification of Letters Patent.

Patented Aug. 8, 1905.

Application filed February 20, 1905. Serial No. 246,391.

To all whom it may concern:

Be it known that I, EDWARD CLYDE HOWLAND, a citizen of the United States, residing at New Milford, in the county of Litchfield and State of Connecticut, have invented certain new and useful Improvements in Puzzles, of which the following is a specification.

This invention relates to improvements in puzzles of that class in which a plurality of balls are contained in a box in which receptacles are provided to receive the balls, and the object is to have all the balls in the receptacles at the same time.

In the accompanying drawings, which form a part of this application, Figure 1 is a top plan view of a puzzle constructed according to my invention. Fig. 2 is a cross-section on the line 2 2 of Fig. 1.

Referring to the drawings in detail, *a* represents the bottom of a cylindrical box having vertical sides *a'*, to which a glass cover or top *a''* is secured. In the center of the box and preferably formed integrally therewith is a circular portion *a''*, which extends to the under side of the glass cover. Secured in the vertical wall of the portion *a''* are four screw-eyes *b*, the rings of which are horizontal. In front of each screw-eye is a pin *c*, which serves as a guard and renders difficult getting the balls

into the screw-eye rings. The number of screw-eyes may be increased, but there will always be a ball, as *d*, provided for each screw-eye, the diameter of the ball being such that it will rest in the screw-eye ring and be supported thereby.

In practice the box will be preferably made of wood, but any other suitable material may be used. The screw-eyes will be placed close to the bottom of the box, so that a slight upward movement or jerk of the box will serve to project the balls into the rings of the screw-eyes.

Having thus described my invention, what I claim as new, and desire to secure by Letters Patent, is—

In a puzzle, a box having a glass cover and centrally-arranged cylindrical portion, rings secured to said portion and projecting therefrom in horizontal position, pins set vertically in proximity to said rings, and balls arranged loosely in said box and adapted to be received and supported by said rings.

In testimony whereof I affix my signature in presence of two witnesses.

EDWARD CLYDE HOWLAND.
